O. SHIRLEY.

UMBRELLA.

APPLICATION FILED DEC. 31, 1915.

Patented July 17, 1917.

his Attorney,

UNITED STATES PATENT OFFICE.

OLIVER SHIRLEY, OF NOWRYTOWN, PENNSYLVANIA.

UMBRELLA.

1,233,718.

Specification of Letters Patent.

Patented July 17, 1917.

Application filed December 31, 1915. Serial No. 69,584

To all whom it may concern:

Be it known that I, OLIVER SHIRLEY, a citizen of the United States, residing at Nowrytown, in the county of Indiana and

5 State of Pennsylvania, have invented certain new and useful Improvements in Umbrellas, of which the following is a specification, reference being had therein to the accompanying drawing.

10 This invention relates to umbrellas and has for its object the production of a simple and efficient foldable umbrella comprising a plurality of collapsible and foldable sections, which sections may be extended to the 15 desired position for supporting the umbrella cover in a taut or tight position and if so desired may also be folded to accommodate the minimum amount of space.

Another object of this invention is the 20 production of a simple and efficient means for producing a collapsible or telescoping standard for a foldable umbrella and holding the umbrella in a rigid folded position.

A still further object of this invention is 25 the production of a simple and efficient foldable joint for each rib of the umbrella.

With these and other objects in view, this 30 invention consists of certain novel combinations, constructions, and arrangements of 35 parts as will be hereinafter fully described and claimed.

In the accompanying drawings:—

Figure 1 is a vertical section through a 35 portion of the umbrella, the standard being shown in elevation.

Fig. 2 is an enlarged vertical section taken on line 7—7 of Fig. 1.

Fig. 3 is a sectional view through the 40 standard of the umbrella, showing the ribs in elevation.

Fig. 4 is an enlarged vertical section of the umbrella cap.

Referring to the accompanying drawings by numerals it will be seen that 1 designates 45 the grip portion of the handle which engages the intermediate body portion 2 of the standard, the intermediate body portion 2 supporting in turn the upper sections of the umbrella standard. The grip portion 1 of the umbrella standard is internally threaded for receiving the lower threaded 50 end of the intermediate section 2 of the umbrella standard. A spring latch 4 is pivotally supported upon the bracket 5 carried by the hand grip 1. The spring 55 latch 4 projects through the aperture 6

formed in the hand grip 1 of the standard of the umbrella. The upper end of the intermediate section 2 of the standard is internally threaded as indicated at 7 in Fig. 2 60 of the drawings and this internally threaded end 7 receives the externally threaded end 8 of the top section 3. The lower end of the depending portion 9 of the top section 3 receives a wedge 12 for enlarging the 65 lower end of the depending portion 9 and constituting a filler for the lower end of section 1.

A cap 13 is fixedly secured to the upper 70 end of the top section 3 of the standard and carries a coiled spring 14 which coiled spring is adapted to engage the rib bracing sleeve 15 slidably mounted upon the top section 3 of the standard. This sleeve 15 engages the brace arms 16 of the ribs and 75 when the umbrella is in a folded position, the upper end of this sleeve 15 engages the lower end of the spring 14 and compresses the same.

The inner sections 17 of the ribs are piv- 80 otally secured to the cap 13 and each inner section 17 of the ribs carries a sleeve 18 provided with depending ears which are pivotally secured to the outer ends of the bracing ribs or arms 16. The sleeve 18 is 85 also provided with upwardly extending ears 19', which ears engage the ears 20 formed upon the inner end of the outer section 21 of the ribs. Each outer section 21 is provided with a pair of spring lips 22, 90 which spring lips 22 are adapted to fit snugly over the projecting end of the inner section 17 of the rib.

From the foregoing description it will be 95 seen that a very simple and efficient umbrella rod has been produced and further that a very simple and efficient bracing rib is provided which is capable of being folded.

The umbrella is arranged in the position shown in Fig. 1 when in a set up position 100 and the usual cover of course is applied to the ribs in the usual manner. When it is desired to fold the umbrella to the position shown in Fig. 3, the outer sections 21 of the ribs are folded backwardly upon the inner 105 sections 17 to the position shown in Fig. 3. The sliding sleeve 15 is then moved upwardly in engagement with the spring 14 and the inner ribs 17 are then folded so as to lie snugly in engagement with the sec- 110 tion 3 of the standard.

The upper section 3 is rotated upon the

intermediate section 2 so as to cause the externally threaded end 8 to disengage the internally threaded end 7 of the intermediate section 2. The upper section is then 5 telescoped within the intermediate section 2 as indicated in Fig. 3 and if so desired, the handle grip 1 may be detached from the intermediate section 2.

By carefully considering Figs. 2 and 3 it 10 will be seen that the wedge 12 is held in engagement with the lower end of the section 3 by means of a pin 12'. A bolt or thumb-screw 13' is threaded through the lower end 15 of the handle 1 and engages the threaded socket 14' formed in the wedge 12 for holding the umbrella in a collapsed or folded position. It will therefore be seen that a 20 very simple and efficient means has been produced for holding the top section 3 in engagement with the handle 1 while the umbrella is in a collapsed condition and that the latch 4 will hold the lower section 2 against accidental unthreading from the 25 grip portion 1 when the device is in a raised position.

It should be understood that when the intermediate section 2 is telescoped within the grip portion 1 and the upper section 3

is folded or telescoped within the intermediate section 2, the pin 13' will be threaded 30 into the socket and thereby hold the entire device in a collapsed condition. It should be understood, however, that the spring latch 4 is merely adapted to hold the intermediate section 2 in its extended position 35 against rotation which would be likely to unthread the intermediate section 2 from the grip portion 1.

What I claim is:—

An umbrella stick of the class described; 40 comprising an intermediate section, a top section, a handle detachably secured to said intermediate section, a spring clip carried by said handle and engaging said intermediate section, said intermediate section 45 provided with an internally threaded upper end, said upper section provided with a depending threaded portion, said intermediate section adapted to receive the threaded end of said upper section, a plug carried by said 50 intermediate section, and a pin engaging said plug for holding said intermediate section in a folded position within said handle.

In testimony whereof I hereunto affix my signature.

OLIVER SHIRLEY.
